UNITED STATES PATENT OFFICE.

ABRAM C. MOTT, JR., OF PHILADELPHIA, PENNSYLVANIA, ASSIGNOR TO ABRAM COX STOVE COMPANY, OF PHILADELPHIA, PENNSYLVANIA, A CORPORATION OF PENNSYLVANIA.

BOILER-FURNACE.

1,262,229.

Specification of Letters Patent. Patented Apr. 9, 1918.

Application filed July 10, 1917. Serial No. 179,678.

To all whom it may concern:

Be it known that I, ABRAM C. MOTT, Jr., a citizen of the United States, residing in Philadelphia, Pennsylvania, have invented 5
Boiler-Furnaces, of which the following is a specification.

This invention relates to steam or hot water heating boilers of the sectional type and one of its objects is to provide a boiler 10 with a furnace so constructed that it shall operate with a high degree of efficiency, particularly as regards the relatively complete consumption of the products of combustion of the fuel and the consequent prevention 15 of smoke.

A further object of the invention is to provide a boiler furnace of the above noted type which shall include a novel arrangement and construction of the independent water containing sections especially designed to insure the heating and delivery of air not only 20 to the body of the fuel in the furnace but also to the space above said fuel and immediately adjacent a heated fire-brick arch.

It is also desired to provide a novel form 25 of section for use in a hot water or steam heater which shall be characterized by a novel disposition and form of air conduit.

These objects and other advantageous 30 ends I secure as hereinafter set forth, reference being had to the accompanying drawings, in which,

Figure 1 is a sectional elevation on the line 1—1, Fig. 2;

Fig. 2 is a sectional elevation on the line 2—2, Fig. 1;

Fig. 3 is a horizontal sectional view on the line 3—3, Fig. 2, of one of the intermediate 40 sections made in accordance with my invention, and

Fig. 4 is a plan of a part of the base casting.

In the above drawings, 15 represents the base casing defining an ash pit and supporting the sections 1—2—3—4 of a sectional steam or hot water heating boiler, of which 45 those sections indicated at 1 and 4 coöperate with said base section to define the sides and portions of the front and back of the boiler proper, and those indicated at 2 and 3 are mounted between the first sections and each 50 also define a portion of the front and back of the boiler.

Said sections are constructed in the well 55 known manner to coöperate with a front cas-

ing 10 and the base casing 15 in defining a hollow space in which are mounted grate bars 6 dividing said space into an ash pit 5 and a furnace 7, and it is noted that said base casing has a series of pockets or bearings 16 at the top of its rear portion for the reception of the ends of said grate bars. Between these pockets are a series of recesses 17 each opening on the front as well as the top edge of said base section. The intermediate sections 2 and 3 are formed to coöperate with the side sections 1 and 4 in supporting a series of flat fire-bricks at the top of the furnace which constitute a fire-brick arch 8 inclined at a slight angle to the 70 horizontal, upwardly from the back to within a short distance of the front of the boiler.

The adjacent faces of the various sections 1—4 are formed to coöperate to provide three separate flues, the entrance 9 to each of 75 which is defined by the front edge of the fire-brick arch 8, the adjacent sections and the inclosing casing or front 10 of the boiler, all of said flues finally discharging into a smoke box 11 at the rear of the boiler. 80

The particular feature of my invention is the peculiar construction of the side and intermediate sections and the base section. It will be noted that each of the side and intermediate sections has a vertical air passage 85 12 therein communicating at its lower end with one of the recesses 17 in the rear of the ash pit casing. The upper end of each passage opens into the combustion chamber of the furnace immediately under the fire brick 90 arch 8 and each of these conduits has a relatively narrow vertical slot 13 in its front wall and extending preferably from the bottom of the section to and communicating with the opening 14, which is elongated, as 95 shown in Fig. 2.

The rear wall and each side of each conduit is surrounded by water in circulation in the boiler, while the front wall is exposed to the burning fuel or products of combustion 100 in the furnace.

Under operating conditions, the fire brick arch 8 is highly heated by the combustion of the fuel in the furnace and air passes from the upper portion of the ash pit through the 105 passages 17 and 12 to the upper portion of the combustion chamber directly under the fire brick arch 8. At the same time a portion of the air will escape through the slots 13 directly at or below the upper surface of 110

the fuel in the fire box, with the result that a thorough combustion is attained and the gases and smoke arising from the fuel are completely burned by the presence of the heated air and the highly heated fire brick arch.

It will be understood that said arch is constantly maintained by the combustion of fuel and gases in the highly heated condition which insures the continuance of this operation, because the air in passing through the conduits 12, is necessarily highly heated before it can escape from the openings 14 adjacent the underside of said arch, so that the boiler will completely burn all smoke forming materials and there will be no unburnt products of combustion delivered to the smoke box and stack.

It is noted that the top openings 17 of the recesses in the base section 15 are laterally elongated in order that the conduits 12 may have full area passageways into the ash pit without forming dust collecting ledges in case any or all of the various sections 1, 2, 3, 4, should be assembled to stand to one side or the other of their proper positions on said base section.

I claim;

1. The combination in a boiler having a furnace and an ash pit, of a fire-brick arch mounted in said furnace; and a series of water-containing sections each formed to provide an air conduit opening at one end into the ash pit and discharging at the opposite end into the top of the furnace under the arch, said conduits having relatively narrow slots opening into the furnace.

2. The combination in a boiler having an ash pit and a furnace, of a fire-brick arch

mounted in said furnace; with a series of 40 water containing sections each having an air conduit positioned with a wall exposed to the furnace, each of said conduits having its lower end connected to the ash pit and at its upper end discharging directly into the top 45 of the furnace under the arch, there being a relatively narrow slot through the heated wall of each conduit for substantially its entire length.

3. The combination in a boiler of an ash 50 pit casing having recesses opening on its interior vertical surface and also on its top edge; a grate; with a plurality of sections mounted on said casing and having vertically extending conduits registering at their 55 lower ends with the recesses in the ash pit casing and opening at their upper ends into the space above said grate constituting the furnace, there being vertically extending slots in the walls of said conduits, opening 60 into the furnace.

4. The combination in a boiler of an ash pit casing having recesses opening on its interior vertical surface and also on its top edge; a grate having members extending at 65 their rear ends into pockets formed in the ash pit casing between said recesses respectively; with a plurality of sections mounted on said casing and having vertically extending conduits registering at their lower ends 70 with the recesses in the ash pit casing and opening at their upper ends into the space above said grate constituting the furnace, there being vertically extending slots in the walls of said conduits opening into the fur- 75 nace.

In witness whereof I affix my signature,
ABRAM C. MOTT, JR.
